Attorney.

UNITED STATES PATENT OFFICE.

EDGAR D. DICKINSON, OF BEVERLY, MASSACHUSETTS, ASSIGNOR TO GENERAL ELECTRIC COMPANY, A CORPORATION OF NEW YORK.

METHOD OF MANUFACTURING NOZZLE DIAPHRAGMS, TURBINE WHEELS, AND THE LIKE.

Application filed March 9, 1927. Serial No. 174,050.

The present invention relates to the manufacture of articles comprising a plurality of partition members arranged and held between two holding members, and is particularly applicable to the manufacture of turbine diaphragms and turbine wheels, although it is not necessarily limited thereto. The object of the invention is to provide an improved method whereby such articles can be manufactured at a low cost but at the same time with a high degree of accuracy, and for a consideration of what I believe to be novel and my invention, attention is directed to the accompanying description and the claims appended thereto.

In the drawing, Fig. 1 is a transverse sectional view illustrating parts used in carrying out my invention; Fig. 2 is a development of a sectional view through the nozzle partition members shown in Fig. 1; Fig. 3 is a top plan view partly broken away of the parts shown in Fig. 1; and Fig. 4 is a radial, sectional view on a larger scale.

In carrying out my invention in connection with the manufacture of a nozzle diaphragm for elastic fluid turbines, I provide a base plate 5 which forms a fixture for use in carrying out my invention, and an inner ring 6, an outer ring 7 and a suitable number of nozzle partitions 8 which form the nozzle diaphragm. Base plate 5 is circular and is provided with an annular raised portion 9 on its top face, having a flat top surface of a width equal substantially to the length of the nozzle partitions and an inner diameter such that inner ring 6 fits inside of it. The annular raised portion is of a height such that it serves to correctly position the discharge edges 10 of the partition members 8. The partition members 8 may have perfectly smooth ends and hence may be cut from strips of stock of the desired cross section, which strips may be made by drawing the strip material through suitable dies. This means that the partition members may be manufactured at a low cost.

I provide the inner ring member 6 in its peripheral face with a series of circumferentially-spaced holes 11 adapted to receive pins 12, the holes being spaced apart so as to position correctly the admission ends of the partition members 8 relatively to each other. Also, I provide the partition mem-

bers 8 in one end with holes 13 adapted to receive pins 12.

In assembling the structure, I first place inner ring 6 on base plate 5 as shown in Fig. 1, after which I assemble around it the partition members 8, each partition member being supported at what is then its upper end by a pin 12, the discharge ends 10 of the nozzle partitions resting on raised portion 9. The partition members are assembled entirely around inner ring 6. This assembling operation can be carried out quickly and with relatively unskilled labor since the nozzle partitions are definitely positioned by pins 12 and the top surface of raised portions 9. In this connection, I consider the use of a flat surface, such as the surface of raised member 9, for positioning the edges 10 of the nozzle partitions as being a particularly advantageous feature of my invention, since it provides a very simple and easy means for getting all the edges even and correctly spaced. Pins 12 fit tightly enough in holes 11 and 13 to hold the members 9, but at the same time permit them to be turned so that edges 10 lie on the smooth top surface of the fixture.

After the partition members have been thus assembled around the inner ring 6, I then shrink outer ring 7 around their outer ends, the ring 7 then having the position shown in Fig. 1. After ring 7 cools, the structure is held rigidly assembled with the partition members 8 correctly positioned between inner ring 6 and outer ring 7. The assembled structure is now removed from base plate 5, and the rings 6 and 7 and the partition members are then permanently united by fusion of metal, as by welding, brazing, soldering or the like. Any suitable method of uniting by fusion of metal may be employed, but preferably I employ the method disclosed in the patent to Steensstrup, No. 1,528,581, Patented March 3, 1925.

After the structure has been united by fusion of metal it may be then finished to the desired contour. In the present instance, the ring member 6 forms the web or central portion of a nozzle diaphragm and the ring member 7 forms the rim of a nozzle diaphragm.

The application of my invention to the manufacture of bucket wheels for turbines

and other similar structures will be understood readily from the foregoing description. In the case of turbine wheels, fluid-directing elements in the form of buckets will replace 5 the fluid-directing elements in the form of nozzle partitions in the structure described.

It will be seen that by the use of my invention I am enabled to use fluid-directing elements, that is, turbine nozzle partitions 10 or the like, which require no special shaping or finishing on the ends; and that, likewise, I can utilize inner ring members and outer ring members requiring no specially shaped finishing. This reduces very materially the 15 cost of manufacture. At the same time, however, a strong and accurately dimensioned product will result.

In accordance with the provisions of the patent statutes, I have described the principle of operation of my invention, together with the particular method which I now consider to represent the best manner for carrying it out, but I desire to have it understood that the particular method disclosed 25 is only illustrative and that the invention may be carried out with such modifications as come within the scope of the appended claims.

What I claim as new, and desire to secure 30 by Letters Patent of the United States, is:

1. The method of manufacturing a structure comprising a plurality of partition elements held between two annular carrying members which comprises placing the inner 35 annular carrying member on a base plate, assembling partition elements individually in spaced relation around the periphery of said inner carrying member with their lower edges resting on the base plate to position them correctly angularly, and then shrinking 40 the outer annular carrying member around the outer ends of the partition elements.

2. The method of manufacturing a structure comprising a plurality of partition elements held between two annular carrying members which comprises placing the inner 45 annular carrying member on a base plate, assembling partition elements individually in spaced relation around the periphery of said inner carrying member by supporting 50

their upper edges on pins, the lower edges resting on the base plate to position them correctly angularly, and then shrinking the outer annular carrying member around the 55 outer ends of the partition elements.

3. The method of manufacturing a structure comprising a plurality of partition elements held between two annular carrying members which comprises placing the inner 60 annular carrying member on a base plate, assembling partition elements individually in spaced relation around the periphery of said inner carrying member with their lower edges resting on the base plate to position them correctly angularly, shrinking 65 the outer annular carrying member around the outer ends of the partition elements, and then removing the structure from the plate and uniting it permanently by 70 fusion of metal.

4. The method of manufacturing a structure comprising a plurality of partition elements held between two annular carrying members which comprises placing the inner 75 annular carrying member on a base plate, assembling partition elements individually in spaced relation around the periphery of said inner carrying member by supporting their upper edges on pins, the lower edges resting on the base plate to position them correctly angularly, shrinking the outer annular carrying member around the outer 80 ends of the partition elements, and then removing the structure from the base plate 85 and uniting it permanently by fusion of metal.

5. The method of manufacturing a nozzle diaphragm which comprises placing an inner annular carrying member on a base plate 90 which presents a surface for positioning the edges of the nozzle partitions, assembling nozzle partitions individually in spaced relation around the member by mounting them on projecting pins carried by the member, the edges of the partitions resting on said 95 surface, shrinking an outer ring around said partitions, and then uniting the assembled structure by fusion of metal.

In witness whereof, I have hereunto set 100 my hand this 5th day of March, 1927.

EDGAR D. DICKINSON.
